UNITED STATES PATENT OFFICE

HENRY C. PAULSON, OF CLEVELAND, OHIO, ASSIGNOR TO THE PROOF MACHINE AND
BRASS FOUNDRY COMPANY, OF CLEVELAND, OHIO

AUTOMOBILE MIRROR

Application filed February 25, 1929. Serial No. 342,496.

This invention relates to new and useful improvements in supports and more particularly to those forms of supports classified as brackets.

5 An object of the invention comprehends the provision of an attaching arm adapted to be carried by and adjustably mounted upon the barrel of a hinge.

An additional object of the invention consists in the provision of a complementary arm carried upon the opposed end of the hinge pin.

A further object of the invention embodies a socket member carried by the complementary 15 arm.

More specifically stated the attaching arm is provided with a connecting pin receivable by the socket member.

With the above and other objects in view, 20 the invention further consists of the following novel features and details of construction, to be hereinafter more fully described, illustrated in the accompanying drawings, and pointed out in the appended claim.

25 In the drawings:—

Figure 1 is an elevation of the improved form of bracket as applied and in use upon the door hinge of a motor vehicle.

Figure 2 is a horizontal sectional view 30 taken on line 2—2 of Figure 1.

Figure 3 is a vertical sectional view taken on line 3—3 of Figure 1.

Referring to the drawings in detail wherein like characters of reference denote corresponding parts, the reference character 10 indicates an attaching ear apertured upon one end thereof to accommodate a complementary hinge pin 11, the latter being employed in place of the conventional form of hinge pin, not shown, employed in the hinge 12 to hinge the door 13 of a vehicle upon the adjacent post 14, after the manner of motor vehicle body construction.

An extension 15, carried by and depending 45 from the outermost end of the ear 10 in right-angularly disposed relation thereto, projects downwardly for an appreciable distance in spaced parallelism with the barrel of the hinge.

50 An attaching arm 16, carried by and out-

wardly projecting from the extension 15, carries a frame 17 upon the outermost end thereof to support a mirror or other reflecting element. A ring, such as indicated at 18, projecting centrally from the back of the frame 55 17, receives the outermost projecting end of the attaching arm 16 in the manner shown in Figures 1 and 2 of the drawings. An enlargement 19, formed upon the attaching arm 16, abuts one side of the ring 18 whereas a 60 fastening element, in the nature of a nut 20, is threaded upon the reduced end of the attaching arm to provide the necessary adjustment for the mirror frame 17.

A complementary attaching ear 21, constructed after the manner of the attaching ear 10 and apertured to accommodate the depending end of the hinge pin or bolt 11, also carries an extension 22, corresponding to that of the extension 15. A socket or sleeve portion 23, carried by and formed as a continuation of the extension 22 and upstanding for appreciable distances above the complementary attaching ear 21, accommodates the lowermost projecting end of a pin member 24, depending from the juncture of association of the attaching arm 16 with the extension 15 of the attaching ear 10, and within the bore thereof.

From the application of the present invention, it is obviously apparent that a rear view mirror is provided upon the left or right hinge of door of a closed model motor vehicle. The connection, as established between the attaching arm 16 and the hinge 12, will facilitate swinging movement of the attaching arm 16 whereby the mirror may be properly focused for the convenience of the driver.

Although the present form of bracket has been shown applied and illustrated upon the door hinges of motor vehicles, it is obviously apparent that the attaching ears 10 and 21 respectively may be effectively employed upon the sleeve end of any sort of arm positioned in any likely place where a rear view mirror may be desired.

The only change necessary in the proper employment of the present invention upon the hinges of motor vehicle body hinges is in the removal of the customary hinge pins 100

and the substitution of the bolt members or pins 11; the latter being long enough to project through the additional thicknesses of attaching portions for the ears 10 and 21.

5 The invention is susceptible of various changes in its form, proportions and minor details of construction, and the right is here-in reserved to make such changes as properly fall within the scope of the appended claim.

10 Having thus described the invention, what is claimed is:—

15 An attaching bracket for mirrors upon the door hinges of motor vehicles comprising complementary attaching ears receiving the terminal ends of the hinge pin therethrough, extensions carried by and depending from the outermost projecting ends of said ears, an attaching arm for the mirror carried by one of the extensions, a sleeve member mounted upon and upstanding from the remaining extension and spaced from the adjacent end of the first mentioned extension, and a pin member carried by and depending from the first mentioned extension projecting terminally thereof within the bore of said sleeve.

20 25 In testimony whereof I affix my signature.
HENRY C. PAULSON.
